UNITED STATES PATENT OFFICE.

THOMAS McCORMICK, OF NEW YORK, N. Y.

HAND-PROPELLED VEHICLE.

1,196,129.

Specification of Letters Patent. Patented Aug. 29, 1916.

Application filed October 15, 1915. Serial No. 56,158.

To all whom it may concern:

Be it known that I, THOMAS McCORMICK, a citizen of the United States, and a resident of New York, in the county of Bronx 5 and State of New York, have invented certain new and useful Improvements in Hand-Propelled Vehicles, of which the following is a full, clear, and exact description, whereby any one skilled in the art may make and 10 use the same.

This invention relates broadly to vehicles, but more particularly it concerns those of the hand propelled type.

One of the objects of the invention is to 15 provide a structure which will be simple and easy in operation, as the device is intended primarily for the use and amusement of children. Another object is to simplify the construction in that I have provided a minimum 20 number of moving parts, thus reducing friction and consequent wear.

Other objects will be in part obvious, and in part pointed out hereafter.

The invention accordingly consists in the 25 features of construction, combination of elements and arrangement of parts which will be exemplified in the device hereinafter described and the scope of the application of which will be indicated in the appended 30 claim.

In the accompanying drawings, wherein is illustrated one of the various possible 35 embodiments of my invention, Figure 1 is a top plan view, and Fig. 2 is a vertical section, partly in elevation.

Similar reference characters refer to similar parts throughout the several views.

This invention in general seeks to provide 40 a device of the class described which from a practical standpoint will in usage possess a high degree of efficiency, and which structurally considered will embody the essence of simplicity, being composed of but few parts, each adapted for being constructed at a minimum of cost, and individually 45 of such a nature as to be capable of being readily assembled by any person skilled in the art.

Referring now to the drawings, the numerals 1—1 denote the front or driving 50 wheels, and 2—2 the rear wheels of the device which is of the four wheeled type. The

front wheels are rigidly affixed, one at either end of a shaft 3 having in the center a crank with arms 4. Suspended from the shaft 3 55 by means of side plates 5—6 is a base board 7.

The rear wheels 2—2 are arranged to revolve upon a shaft 8 and suspended from this shaft by means of bearings 9—10 is a floor 60 plate 11 carrying by means of the brackets 12—12 the seat 13. A bolt 14 passes through the floor board 11, spacing washers 15, and base board 7, on the under side of which the bolt is secured by means of the nut 16. The 65 bolt 14 therefore acts as a king bolt, or pivot between the floor board, 11, and the base board 7 allowing a turning movement between them in a horizontal plane.

On either side of the bolt 14 and near the 70 forward edge of the base board 7 are placed foot rests 17 and 18. A handle or wrist-pin 19 is rotatably secured between the crank arms 4—4.

The operation of the device is as follows: 75 The operator seats himself upon the seat 13 and places one foot on each of the rests 17 and 18. He then grasps the wrist-pin 19 in either hand and by turning the crank arms 4 motion is communicated directly to 80 the front wheels. The device can be driven in either a forward or backward direction by simply turning the crank in the proper direction. At the same time by exerting a pressure with either foot upon one of the 85 foot rests, the floor board 11 and appurtenant parts are caused to assume an angular position with respect to the base board 7, thus steering the device. It is obvious that as only one hand is necessary to operate 90 the crank, the other hand may be employed to assist in steering when desired by grasping one of the side plates 5—6 and exerting pressure in the proper direction. A handle or pull cord might also be attached to the 95 base board 7 if desired so that the device could be towed when necessary.

What I claim as my invention and desire to secure by Letters Patent is:

In a device of the class described, in combination, a frame or body having a shaft arranged to be rotated in bearings secured to the forward part of said frame, said shaft being provided with steering and driving

wheels fixedly secured upon either end and having a crank arm intermediate said wheels, a seat forming the rear part of the body mounted upon rollers or small wheels 5 for the support of the rider, and a pair of upright-attached foot-rests by the use of which the rider's feet communicate a turn-

ing movement to the steering and driving wheels, substantially as described.

THOMAS McCORMICK.
